UNITED STATES PATENT OFFICE

HARRY OVERBERG, OF CINCINNATI, OHIO

LURE CARRIER

Application filed June 16, 1930. Serial No. 461,423.

This invention relates to an electrically-motivated car adapted for use at dog-racing tracks in carrying around the course the ruse or lure, generally in the form of a dummy rabbit.

An object of the invention is to provide improved means of the class described having new and simplified features both of mechanical structure and of electric motivation.

10 Another object is to provide such a device which practically eliminates the possibility of removal from its tracks during operation.

Another object is to provide such a car which is substantially lighter in weight than 15 those heretofore constructed and which is compact and readily portable.

These and other objects are attained by the means disclosed herein and illustrated in the accompanying drawings, in which:

20 Fig. 1 is a side elevational view of the car of this invention mounted upon its tracks.

Fig. 2 is a view taken on line 2—2 of Fig. 1.

Fig. 3 is a longitudinal section through 25 one of the electric brush supports of the invention.

Fig. 4 is a side elevation of a modified form of electrical brush associated with a wheel, parts being broken away.

Fig. 5 is a detail view of the contact wheel 30 shown in Fig. 4.

Fig. 6 is a view taken on line 6—6 of Fig. 4.

Fig. 7 is a vertical sectional view of another modified form of current carrying means of the invention.

35 Fig. 8 is a side elevation of modified guide means.

The device of this invention is adapted to run upon surface tracks which are endless and coextensive with the racing course which 40 is generally oval in form. The tracks run immediately adjacent the inner edge of a fenced-in racing course into which the dummy rabbit, carried by the car upon the opposite side of the inner fence, is projected. 45 These general features are known and need not be further detailed. However, it should be remarked that prior devices of the class of this invention have been adapted to run, either in a pit or ditch extending directly beneath the race course, or else have provided

for the overhead conveyance of a suspended dummy rabbit, both of which types involved much expensive structural work. The present invention provides a surface-running car requiring considerably less associated structure than heretofore used and in which the dummy rabbit is carried laterally of the car. 55

With reference to the drawings: the car or carrier comprises the motor 10 and commutator 11 supported upon the central shaft 12. Shaft 12 is fixedly journaled at its ends in the grooved wheels 13 and 14 adapted to run upon the vertical ribs 15 of the surface tracks 16. The outer casing of motor 10 is provided with a pair of spaced, outwardly-projecting flanges 17 and 18 extending horizontally over the motor and vertically of its sides. The ends of flanges 17 and 18 project beneath the motor and are formed with feet 19 between which a cross plate 20 extends. A one-piece trolley frame 21 has a central portion passing horizontally beneath the motor 10 transversely thereof and secured upon the upper face of cross plate 20. Frame 21, extends upwardly above the 70 motor 10 and wheels 13 and 14 and comprises a pair of divergent arms having the intermediate angled portions 22 and 23 and the vertical end portions 24 and 25. A strengthening bar 37 may be positioned between the 75 divergent arms. Mounting members 26 and 27 are attached upon portions 24 and 25 and are vertically adjustable thereof as indicated at 28. The upper parts of members 26 and 27 are box-like in form and are provided 80 each with a vertical passage 29 within which the pin 30 of bifurcated swivel members 31 extends. Each pin 30 rests upon and normally is urged upwardly by a coil spring 32 disposed upon the base of passage 29. A 90 pulley 33, provided with roller bearings, is carried by each swivel member 31. Pulleys 33 are adapted to run upon a single track 34 carried by suitable supporting structure 35 erected at one side of tracks 16 and having 95 overhanging arms 36. The relationship of pulleys 33 and track 34 is such that the pulleys, when both are in position, are depressed against the tension of coil springs 32. It will be seen that by this balanced 100

structure, the car is retained in proper operative position upon its tracks. It should be noted that the groove walls of wheels 13, 14, and 33 have sufficient pitch to allow for unimpeded movement of the car around the curved portions of its track.

Electric power is transmitted to the car through the tracks 16 into the motor, one of the tracks serving as the carrier and the other as the return conduit. Several means are herein set forth for transmitting the current from the rails 16 into the motor. In all of these forms it is necessary that wheels 13 and 14 be insulated from the motor shaft 12. This structure is illustrated in Fig. 6. Each end of shaft 12 is threadedly received by a fiber bushing 38 disposed in the wheel bearing 39 and projecting outwardly a short distance beyond each side of the wheel. These projecting portions 40 are surrounded by a fiber washer 41 which extends outwardly beyond said ends 40 of the bushing. A flanged nut 42 is threadedly received upon shaft 12 on each side of the wheel and is brought into firm contact against the adjacent washer 41. The wheel and shaft are keyed together by means of a fiber pin 43 passing through nut 42, washer 41 and into the wheel.

The track-to-motor circuit means likewise comprise a pair of pipe arms 44 and 45 extending from a support box 46 secured upon the flanges 17 and 18 at one side of the motor 10. Arms 44 and 45 each threadedly receives at its free end a T-connection which is spaced from and in substantial parallelism with the adjacent car wheel. The motor wires 48 extend into support box 46 and through arms 44 and 45 as will be further explained.

In Figs. 1 and 2 and 3 the outer portion of each T-piece 47 is provided with a fiber bushing 49 the ends of which extend beyond the ends of the T-piece. A metal pin 50, as of bronze, extends through and beyond the bushing 49 and threadedly receives at each end a nut 51 and 52, respectively; which abut the ends of the bushing 49. A slot 53 in the upper end of pin 50 has secured therein, such as by soldering, the end of a copper strip 54, which serves as an electrical contact brush. A threaded bolt 55 in the edge of nut 51 is used for attaching the free end of motor wire 48 to said nut. The T-connection 47 is adapted to be adjustably fixed in an angular relationship relative to the adjacent wheel for bringing the brush 54 into contact upon the periphery of the car wheel. It is evident that an electrical circuit has been established through rails 16, wheels 13 and 14, brushes 54, pins 50, wires 48 and motor 10.

A modified form of circuit means is shown in Fig. 4. Herein a fiber shaft is adjustably secured in and projects outwardly beyond the ends of the vertically-disposed T connec-

tion 47. A metal pin 57 extends through the upper end of shaft 56, toward the adjacent car wheel, and has a swivel member 58 attached to the end adjacent the wheel. A centrally ribbed roller wheel 59 is mounted in member 58 and is urged against the periphery of the adjacent wheel by means of a spring 60 disposed on pin 57 between swivel member 58 and shaft 56, tension of this spring being adjustable by means of a nut 61 threadedly received upon the outer end of pin 57. The ribbed portion of roller 59 is adapted to extend into the grooved portion of the wheel and the lateral sections thereof are adapted to ride upon the periphery of the wheel. Motor wire 48 may be connected to pin 57 between nut 61 and shaft 56.

A third circuit means is illustrated in Fig. 7. Herein a shoe 62, adapted to ride upon a horizontal section 63 of track 16, is substituted for the brush means of the two previously described means. Shoe 62 has a central stem 64 projecting upwardly into a fiber tube 65 suitably attached, as at 66, to the lower end of the vertically disposed T-connection 47. A coil spring 67 disposed interiorly of tube 65, encloses stem 64 and seats upon shoe 62. A metal screw 68 is threadedly received in a fiber core 69 in T-piece 47, and projects downwardly into tube 65, having an abutment plate 70 on its lower end adapted to contact spring 67, whereby tension of the spring is adjustable by movement of screw 68. The motor wire is attached to shoe 62 as at 71 and passes upwardly into the adjacent pipe arm through a perforation 72 therein.

A dummy rabbit 73, or the like, may be attached at the end of a vertical rod 74 connected to a rigid support arm 75 extending from the car and over the adjacent fence surrounding the race course. Arm 75 may be removably attached to the car by means of a support block 76 secured upon the top of flanges 17 and 18 and having an arm-receiving passage 77 with a threaded bolt 78 projecting thereinto.

The commutator 11 may be provided with removable shield means 79 by which access may be had to the adjacent parts and the latter protected from dirt and foreign matter.

Fig. 8 illustrates a modified form of upper guide structure. Herein, the pulley 33 is pivotally mounted in the hook portion 80 of a short vertical arm 81 having offsets as at 82 and 83 for bringing said hook portion into alignment with the upwardly disposed guide rail 34. Arm 81 passes loosely through journal member 84 secured in cross bar 37 adjacent the end thereof. The lower end of arm 81 projects below the bar 37 and has a coil spring 85 thereon which abuts the member 84 at its top end and the adjustable plate 86 at its lower end. The arms of frame 21 are secured as at 87 to the ends of cross bar 130

37. Spring 85 serves to retain pulley 33 in constant contact with its rail 34, compensating for possible irregularities in the surface tracks, or in said rail.

5 Electric current passed through one of the circuits previously described results in movement of the carrier about its track. A reversible variable speed motor and control having a plurality of speeds, may be used. The 10 common practice at the finish of a race is to drop a curtain, across the course, shutting off the rabbit from the view of the dogs. After this, the electric current is cut off and the car is permitted to come to a stop.

15 The device of this invention is compact and readily transported, and is comparatively light in weight, yet any danger of removal from its track while in use is practically eliminated by its novel form of mounting and 20 the balanced retaining forces acting thereon. Due to the simplicity of its construction it has the added advantage of a low manufacturing cost.

What is claimed is:

25 1. The combination with a pair of endless metal tracks, of a device adapted to run upon said tracks and comprising a pair of metal wheels fixed upon a common shaft and electrically insulated from said shaft, a motor 30 mounted upon the shaft intermediate the wheels and adapted to drive the shaft, a pair of parallel arms attached one each to one side of the motor and extending upwardly therefrom in divergent relationship, an 35 overhanging support structure erected at one side of the tracks, a flanged rail attached to the overhanging portion of said support above and in alignment with said divergent arms, a pulley pivotally mounted at the upper 40 end of each of said arms, means normally urging the pulleys upwardly into association with said flanged rail and means attached to the car and normally contacting the wheels thereof, said means being electrically connected to the motor whereby electric current 45 passed through the tracks is transmitted to the motor for effecting movement of the car upon the tracks.

2. In a lure carrier the combination of a 50 pair of surface tracks, an elevated guide disposed in a plane parallel with and intermediate the surface tracks, a motor having an extended armature shaft, tractional supporting wheels on said shaft, electrically insulated therefrom and engaging the surface tracks, the surface tracks carrying electrical current for the motor, brush means electrically connecting the motor with said tracks, a 55 frame member attached to the motor and extending above it and having a pair of tractional means engaging the elevated guide, and means carried by the motor and extending transversely of the track for suspending a lure closely adjacent the plane of the surface 60 tracks.

3. In a lure carrier the combination of a pair of surface tracks, an elevated rail disposed in a plane intermediate said tracks, a shaft, wheels rigidly mounted in electrically insulated relation on said shaft and adapted to run on said surface tracks, electrical motor means supported by said shaft and having driving relation therewith, means on the motor tractionally engaging the elevated rail for stabilizing the motor on its supporting shaft, and brush means contacting said wheels and electrically connecting the motor and the tracks.

4. In a device of the class described a motor comprising a stator and an armature, an armature shaft extending on both sides of the motor, tractional supporting wheels fixed on said shaft and electrically insulated therefrom, a frame extending above the motor and adapted for tractional engagement upon an elevated rail, and means to supply energizing current to the motor.

5. A lure carrier adapted to run upon electrically-energized tracks and comprising a shaft, wheels fixed upon the shaft and electrically insulated therefrom the wheels being adapted to run upon said tracks, a motor mounted upon the shaft in driving relationship therewith, means for energizing the motor from the current carried by the tracks, a frame secured upon and extending above the motor and projecting forwardly and rearwardly of the motor in substantial parallelism with the tracks, means disposed above the tracks and adapted to engage said frame for maintaining cooperative relation of the wheels and motor with said tracks, and means on the motor for supporting a lure.

In testimony whereof, I have hereunto subscribed my name this 24th day of May, 1930.

HARRY OVERBERG.
